ATTORNEY

UNITED STATES PATENT OFFICE.

CHARLES H. BICALKY, OF MINNEAPOLIS, MINNESOTA.

FURNACE.

SPECIFICATION forming part of Letters Patent No. 372,738, dated November 8, 1887.

Application filed February 3, 1887. Serial No. 226,344. (No model.)

To all whom it may concern:

Be it known that I, CHARLES H. BICALKY, a citizen of the United States, residing at Minneapolis, county of Hennepin, State of Minnesota, have invented certain new and useful Improvements in Furnaces, of which the following is a specification, reference being had to the accompanying drawings.

My invention relates to heating-furnaces, and has for its object to save and utilize a large amount of heat, which is ordinarily wasted by passing out through the flues and chimneys into the open air. I accomplish this result by a greatly-increased radiating surface interposed between the burning fuel and the chimney-flue.

In furnaces now in general use only a fraction of the heat given off by the burning fuel is made available for use. The balance passes up the chimney. The flue-pipe will be red-hot, while the rest of the furnace (except the fire-pot) remains at a comparatively low temperature. I overcome this radical defect by a construction simple, economical, and efficient, and maximize the available heat from any given quantity of fuel.

My invention consists of the construction hereinafter fully described and particularly claimed.

In the drawings, like letters referring to like parts throughout, Figure 1 is a vertical central section, on line Y Y' of Fig. 2, of a furnace embodying my improvements. Fig. 2 is a plan on the line X X' of Fig. 1, and Fig. 3 is a detail showing my means of supporting the grate.

A is the fire-pot, B the ash-pit, and C the smoke-dome, of an ordinary furnace. The dome is made of steel, and the fire-pot has straight walls. The fire-pot is preferably corrugated, and is made in two sections, (instead of one, as shown.)

D is a primary or direct draft radiator. It is in shape like a closed section of a pair of concentric cylinders, or may be described as an annular drum. It surrounds the steel dome, the tops of the two being on the same level, and is supported in position with several inches clear space between the outside walls of the dome and the inside walls of the radiator.

The radiator D communicates directly with the steel dome through the direct-draft flue E

in front, and with the chimney through the smoke-flue F, placed in the rear diametrically opposite to the direct-draft flue E.

55

G is my secondary or indirect radiator. It is in shape like radiator D, but has a section cut away in front, the two ends being closed and terminating in front about on the vertical lines of the sides of the fuel and ash doors. It surrounds the fire-pot, with its top below or on a level with the bottom of the steel dome. A somewhat larger free space is left between the radiator and the fire-pot than between the primary radiator and the steel dome. A pair of flues, H and H', connect the radiator G with the steel dome in the rear directly beneath the chimney-flue F. A pair of flues, K and K', connect the extremities of the radiator G in front with the radiator D, as shown, passing up, one each, on the opposite sides of the fuel-opening.

70

In the front of the radiator D, on a line coincident with the direct-draft flue E, is an opening or port-hole, a, and in the flue E is placed a pivoted damper, b, provided with an operating lever or handle, c, which extends outward within the flue E across the radiator, and through the port a to the outside of the radiator. The port a is provided with a suitable cap for tightly closing the same. The furnace is provided with a suitable base-plate, L, and is surrounded by a jacket, (not shown,) with heat-conducting flues to the various rooms to be heated, of the kind in ordinary use.

75

In the radiators D and G, at suitable convenient points, are provided hand-holes d, for cleaning the radiators when required. Suitable caps close the same when the furnace is in use.

80

I use in my furnace the grate M, which is of the ordinary form, except in two respects—viz., it has a serrated or notched edge or teeth on its periphery, and it is supported by journals and rollers on a grooved flange or guide in the ash-pit, a cross-section of which is shown in Fig. 3.

85

N is a pintle or journal integral with the grate and extending beyond the edge of the same. P is a little wheel or roller attached loosely to the journal N, and provided with a raised collar, e, rigid with the wheel. R is the bearing-flange attached to the side walls of the ash-pit, and is provided with a groove, f, of

90

95

100

greater depth than the collar *e*. The roller *P* rests on the flat surfaces of the flange on the groove, with its collar *e* projecting downward in the groove. As many of these grooved flanges and journals with rollers are used as may be required, three of each, the flanges being three or four inches in length, being sufficient.

The purpose of my improved bearing is to secure the grate from displacement under the action of heat or rough usage, and to make it easy to handle. The ordinary grate warps under the intense heat of the fire-pot and easily gets out of its proper position.

15 The purpose of the serrated edge is to avoid clinkers and keep up an even fire on the outside of the body of fuel, as well as in the center.

Over the grate, attached to the walls of the fire-pot adjacent to the grate, hangs an annulus, *S*, having inwardly and downwardly projecting teeth similar to those on the grate. This serrated annulus co-operates with the serrated grate and straight-walled corrugated fire-pot to give a good feed-draft up through the outside layers of coal, and to afford a ready means for the escape of the ashes and clinkers.

In the indirect radiator *G*, between the points where enter the flues *H H'*, may be put a division-plate, if thought desirable; but this is not essential, as the heat and products of combustion will take the shortest course.

The operation of my furnace is as follows: To start the fire most readily, the damper *b* is opened. The products of combustion take the shortest course and pass out of the dome *C*, through the direct-draft flue *E*, to the radiator *D*, and around through the same to the chimney-flue *F*. After the fire has become well established, the damper *b* is closed, thus forcing the flame, smoke, and heat to pass out through the indirect flues *H H'* to the rear of the secondary radiator *G*. Thence a part of it goes each way through the opposite parts of the radiator *G* and up through the flues *K K'* to the

radiator *D*, and thence through the whole 45 length of the same to the chimney-flue *F*. It will thus be seen that I greatly increase the radiating-surface over which the products of combustion must pass before entering the chimney, in virtue of which fact the heat is 50 all utilized instead of being wasted. The location and arrangement of the two radiators are also important features. The radiator *G*, in addition to the heat received from the products of combustion passing through the same, 55 gets a large amount of heat from the fire-pot *A*. In a similar manner the radiator *D* gets heat directly from the steel dome *C*. By the secondary radiator the cold air to be heated inside the jacket is made to pass over a largely- 60 increased hot surface, and is also, by its location, brought into contact with the heating-surface much sooner than in existing forms of furnaces.

My construction enables me to make a very 65 superior furnace in a very compact form, requiring small space, and is simple and cheap to build.

What I claim, and desire to secure by Letters Patent of the United States, is as follows: 70

In a heating-furnace, in combination, the direct radiator *D*, encircling the body of the steel smoke-dome of the furnace, direct-draft flue *E*, provided with the damper *b*, connecting the radiator *D* with said smoke-dome, the 75 chimney-flue *F*, diametrically opposite to flue *E*, the indirect radiator *G*, partially encircling the fire-pot of the furnace, the indirect-draft flues *H H'*, connecting the indirect radiator *G* with the smoke-dome of the furnace, and the 80 flues *K K'*, connecting the extremities of the radiator *G* with the part of radiator *D* most remote from the chimney-flue *F*, all substantially as and for the purpose described.

CHARLES H. BICALKY.
